UNITED STATES PATENT OFFICE.

HILL BERNSTEIN, OF CHICAGO, ILLINOIS.

GAMING DEVICE.

Application filed March 18, 1922. Serial No. 544,756.

To all whom it may concern:

Be it known that I, HILL BERNSTEIN, a citizen of the United States, residing at Chicago, in the county of Cook and State 5 of Illinois, have invented certain new and useful Improvements in Gaming Devices, of which the following is a specification.

This invention relates to a new and improved gaming apparatus and more specifically to a polyhedron having indicia upon its several faces.

Numerous games are played using dice consisting of cubes having their several sides marked, but such dice are open to the 15 objection that they only provide the possibility of placing thereon six different characters. A further difficulty with the use of cube dice lies in the fact that it is possible, by an expert user, to so throw the dice as 20 to cause a predetermined character to be exposed upon the upper side thereof.

It is an object of the present invention to provide a polyhedron having such a 25 number of sides as to be capable of bearing a relatively large number of indicia and which polyhedron is regular in form so that the chances are equal for each of the sides being horizontally exposed upon the upper surface when the gaming device is 30 thrown in play.

It is a further object to provide a device 35 of this character on which various indicia may be duplicated on the several sides, the number of duplications of the different indicia being determined upon a predetermined ratio, such that the probability of the various indicia appearing is definitely proportioned.

Other and further objects will appear as 40 the description proceeds.

I have illustrated a preferred embodiment 45 of my invention in the accompanying drawings, in which—

Figure 1 is a face view of the device; 50 Figure 2 is a view of Figure 1 as seen from above; and

Figure 3 is a diagrammatic, developed view showing the indicia upon all the surfaces of the polyhedron.

The gaming device shown comprises a 55 spherical polyhedron having twenty sides, the sides being identical in shape and size, each side being an equilateral triangle whose plane intersects the plane of each adjoining side at an identical angle. The solid

is thus perfectly symmetrical and the probability of any one side turning uppermost when the ball is thrown in play, is equal to the probability of any other side coming uppermost.

In the particular form shown in the drawings, the several sides have been marked as follows: Two sides have been marked Honest Abe, two sides have been marked J, standing for Jack, three sides 60 have been marked E, standing for Eva, four sides have been marked with A, standing for Abe, four sides have been marked with K, standing for Kate, and five sides have been marked with M, standing for Mabel. 65 It will thus be observed that although the probabilities are equal among the various sides, that the probability of each of the various characters appearing upon the upper side has been definitely fixed by the 70 number of sides upon which each character appears.

A game employing the specific marks shown in the drawing may be covered by 75 rules as follows: The various players may use the device in turn or one player may continue to use it as long as he continues to win. The ball is rolled by being thrown by the hand or from a cup, upon any flat surface. If desired, it may be made to rebound from some vertical surface on to a 80 flat surface.

On the first roll, if the roller meets Honest Abe, that is, causes the character Honest Abe to appear on the uppermost face of 85 the device when thrown, he neither wins nor loses. In this case, the next roll is again counted as the first. On the first roll, if the roller meets Abe, he wins, while if he meets Jack, he loses. On the first roll, if 90 the roller meets Mabel, Kate or Eva, he must continue rolling until he either meets again his particular girl or meets Honest Abe or Abe. If he meets his girl again 95 first, he wins, while if he meets Honest Abe or Abe first, he loses. After having met one of the girls, meeting Jack, he neither wins nor loses.

Obviously, the record of the game may be kept either by means of counters or on 100 scoring devices of any kind. The rules of the game given are by way of example only as obviously the device is capable of various uses in connection with games having other and different rules.

It is my intention to cover all modifications coming within the spirit and scope of the appended claims.

I claim:

- 5 1. A gaming apparatus consisting of a spherical polyhedron having twenty sides of identical shape and size, each face being an equilateral triangle whose plane intersects the plane of each adjoining face at an identical angle, the sides being each marked with a character relating to the game.
- 10 2. A gaming apparatus consisting of a spherical polyhedron having twenty sides

of identical shape and size, each face being 15 an equilateral triangle whose plane intersects the plane of each adjoining face at an identical angle, the sides being each marked with a character relating to the game, two differing characters, each occurring on two faces, another character occurring on three faces, two other different characters each occurring on four faces, and one character occurring on five faces.

Signed at Chicago, Illinois, this 16th day 25 of March, 1922.

HILL BERNSTEIN.
